UNITED STATES PATENT OFFICE

JOHN P. FABER, OF DUNELLEN, NEW JERSEY, ASSIGNOR TO RANSOME CONCRETE MACHINERY COMPANY, OF PLAINFIELD, NEW JERSEY, A CORPORATION OF NEW JERSEY

CHARGING DEVICE FOR CONCRETE MIXERS

Application filed October 4, 1927. Serial No. 223,870.

This is a continuation in part of my application for loader buckets for concrete mixers filed June 2nd, 1925, Serial No. 34,281. In that application I disclosed and claimed a 5 two pivot loader bucket for use in concrete mixers.

The improvements herein relate primarily to such buckets but particularly to the means for elevating same. These loaders or buckets are constructed and arranged to rest on the ground below the charging opening of the mixer so as to receive the aggregates to be mixed from barrows or shovels, or any other manner, near the ground level. The 15 bucket is usually so mounted that as it is raised it also tips or tilts and discharges its load into the mixer. A cable leading from a drum on the mixer frame to the bucket is commonly employed for elevating same. The 20 present improvements are designed to afford a better connection between the cable and bucket, which equalizes the pull of the former and economizes the power required to elevate the load.

25 The improvements are illustrated in the accompanying drawings, in which—

Fig. 1 is a side elevation of a loading bucket with connected parts embodying my improvements;

30 Fig. 2 is a front view of my cable connection member or bail;

Fig. 3 is a detail of the bail; and

Fig. 4 is a plan view of one end of the bail.

The skip or bucket 1 is adapted to be raised 35 or lowered by means of a cable 2 running over sheaves 3 and connected with a suitable power device. 4 is an upright member of the frame of the apparatus, mounted on a base 5, one of said uprights being provided at each side 40 of the mixer (not shown).

A plate 6 with turned strengthening edges is pivoted at 7 in brackets 8 secured on the uprights 4 and extends across from one bracket to the other, and at 9 near the bottom of 45 this pivoted plate, the bucket carrying frames are pivoted. These frames consist of the converging arms 11 and 12 connected by the plate 10 to each other and to the pivot, the brace 18 connecting their outer portions and 50 the widened outer ends 19 and 20 secured to

the upwardly extending portion of the loading bucket or skip 1. The inward movement of the pivoted plate 6 is limited by the stop 13 on base 5 and the inward and upward movement of the bucket carrying frame is 55 limited by contact between the plate 6 at its upper part near its edge and the stop 16 riveted at 17 to the outer portion of frame 11.

As shown, the bucket 1 has a charging portion 21 and a discharging portion 22 at an 60 angle to each other.

On each side of the bucket and near the top thereof is rigidly mounted a lug or ear 24 having apertures 25 in which are disposed the trunnions 26 of a bail or bridge 23. The 65 latter is thus pivotally connected with the bucket on each side so that there is a certain amount of pivotal movement between the bail and bucket. As seen in Fig. 4, the bail comprises beams riveted together having riveted 70 between their ends the trunnions 26. However, I may utilize any other form of bail. Apertures 27 are provided in each side of the bail, and, adjacent thereto, mounted between said beams, are sheaves 28, said sheaves being so 75 positioned that their peripheries are in alignment with said apertures 27. The cable 2 runs over a sheave 3 on one side of the frame at the top, through the bail 23 entering same at one side, through aperture 27, over sheave 80 28 and extending around under it and passing out over sheave 28 and aperture 27 at the other side. Thence the cable 2 runs over sheave 3 on the other side of the frame.

In elevating the bucket to charging position, the foregoing improvements equalize the pull of the cable on the bucket and also protects the cable against undue wear and injury or the deteriorating effect of exposure to the ground, as where it is run under the 90 bucket.

Where one or more pivots are employed in elevating a bucket, it frequently happens that the heavy load of aggregates unevenly distributed develop a torque in the bucket 95 tending to bind at said pivots and therefore calling for additional power to overcome same. However, my construction eliminates this undesirable twisting of the bucket and also economizes power since the endless cable 100

threaded through the apertures in the bail, in conjunction with pivots 24, enables the bucket at all times to automatically adjust itself and the load to swing in the arc of least resistance. Other advantages of the construction will be apparent to those skilled in the art.

What I claim is:

1. A loader bucket having charging and discharging portions at an angle to each other and adapted to be raised and lowered in an arc, a bridge pivotally mounted on said charging portion and extending across same, said bridge having spaced apertures adapted to receive a hoisting cable and means on said bridge aligned with said apertures for bearing said cable.
2. In a device of the character described, a hoisting cable, a loader bucket adapted to be elevated and lowered, a cable connection member disposed over and operatively connected to said bucket, said member having spaced cable receiving members, said cable extending through said members with a portion thereof extending in exposed position along said first named member.
3. A loader bucket adapted to be elevated and lowered having a cable connection member operatively associated therewith, said member having spaced apertures adapted to receive a hoisting cable and removable bearings housed in said member and aligned with said apertures for bearing said cable.
4. A loader bucket adapted to be elevated and lowered having a cable connection member operatively associated therewith, said member extending across said bucket and comprising parallel members connected in spaced relation whereby a hoist cable may pass therebetween, and spaced bearing members disposed between said parallel members for bearing said cable.

Witness my hand this 30th day of September 1927, at Dunellen, N. J.

JOHN P. FABER.
